DESIGN FOR WALLPAPER OR SIMILAR ARTICLE

John W. Orian, New York, N. Y.

Application April 11, 1940, Serial No. 91,612

Term of patent 3½ years

To all whom it may concern:

Be it known that I, John W. Orian, a citizen of the United States, residing at New York, in the county of New York and State of New York, have invented a new, original, and ornamental Design for Wallpaper or Similar Article, of which the following is a specification, reference being had to the accompanying drawing, forming a part thereof.

The single figure is a plan view of a piece of a wallpaper or similar article, embodying my design.

I claim:

The ornamental design for wallpaper or similar article, substantially as shown.

JOHN W. ORIAN.
